(57) **CLAIM**

The ornamental design for a cabinet lock, as shown and described.

DESCRIPTION

FIG. 1 is a front, right side perspective view of a cabinet lock showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged fragmentary front view of the portion shown within the encircled area identified as 8 in FIG. 2. The broken lines represent portions of the cabinet lock that form no part of the claimed design. The dot-dash broken lines represent borders of the claimed design and form no part of the claimed design.

1 Claim, 6 Drawing Sheets
